UNITED STATES PATENT OFFICE.

GEORGE H. FOWLER, OF TAUGHANNOCK FALLS, NEW YORK.

SULKY-PLOW.

SPECIFICATION forming part of Letters Patent No. 334,424, dated January 19, 1886.

Application filed May 16, 1885. Serial No. 165,625. (No model.)

To all whom it may concern:

Be it known that I, GEORGE H. FOWLER, a citizen of the United States, residing at Taughannock Falls, in the county of Tompkins and State of New York, have invented 5 certain new and useful Improvements in Sulky-Plows; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 In these drawings, Figure 1 is a plan view of my sulky-plow, the plow and seat being removed. Fig. 2 is a view of the right side of the same, including the seat. Fig. 3 is a view of the left side. Figs. 4 and 5 are detail views 20 of the same.

Similar letters of reference indicate corresponding parts in all the figures.

My invention has relation to sulky-plows; and it contemplates certain new and useful 25 improvements in the plow for which Letters Patent No. 277,258 were granted to me on the 8th day of May, 1883; and it consists, to that end, in the improved construction and combination of parts of the same, as hereinafter more 30 fully described and claimed.

The frame of my sulky is formed by two pieces of U-shaped iron or wood united at right angles, as shown in the drawings, one piece being substantially horizontal, the other 35 substantially vertical. The pole is attached to the under side of the vertical piece of the frame, and is rigidly fixed to the horizontal piece by braces or like connection. In the rear portion of the horizontal part of the frame is 40 pivoted the bail C.

The coupling B is constructed with slots in each side, through which the bail C of the sulky passes. The play of the bail is limited by dropping bolts in the holes P P through the 45 sides of the coupling forward of the bail.

The construction of the coupler may be considerably modified without departing from the spirit of the invention. It may be made of wood or iron, or partly of wood and iron. The 50 parts of bearing of this coupler on the bail

should extend some distance along the bail in order to secure the best results.

While I have shown the coupler as made of skeleton form, the portion through which the bail passes may be tubular and limited by 55 bolts. Such tube may have more or less play along the bail, as desired.

To the lower ends of the vertical U-shaped pieces are rigidly attached the bearing-plates F F. These are the same on both sides, and 60 are provided each with a circular opening, G, and with a slot, H, curved to conform to a circle, of which the circular opening is the center. These bearing-plates may be provided each with a collar around the circular opening, to furnish a more extended bearing; but this is not in all cases necessary.

The stub-axles J and l consist each of a bar or rod of iron bent into a U shape, one arm, j, of said U-shaped bar, upon which the wheel 70 turns, being longer than the other, j', upon which the axle is supported. The axles are keyed to the bearing-plates F F, the shorter arms passing through the circular openings G G, the longer arms through the slots, and 75 may be removed at pleasure. The bearing-plates F F are rigidly secured to the sulky-frame in such a manner that when the sulky is level on a level surface the land-wheel axle l will be at the lower end of the slot and the 80 furrow-wheel axle J will be at the upper end of the slot, each in its respective bearing-plates.

The lever L is provided with a plate at its lower extremity, having two openings there-through. This plate is placed upon the axle 85 just outside the bearing-plate F, one of the openings passing over the shorter arm of the axle, the other over the longer arm of the same. By means of this lever the land-wheel axle l may be raised or lowered in the slot H 90 of its bearing-plate at the will of the operator, thus keeping the sulky level while plowing.

To the frame is attached a notched segment, and the lever is furnished with a spring-catch to engage the notches in the said segment in 95 ordinary manner. Any other means of controlling the lever may, however, be used. Instead of the plate at the lower end of the lever, there could be a fork, the ends of said fork passing over the arms of the axle; or there may 100

be two pieces of iron at right angles, one end of the horizontal piece of the right angle containing an eye, which passes over the shorter arm of axle, and the other end of the piece passing under the longer arm.

The furrow-wheel M is adjusted by means of the iron strap N, which has at its lower end a collar passing around the axle and is provided with holes, thus allowing a pin or bolt 10 to pass through the strap and frame at any point desired, corresponding holes being made in the frame.

If desired, instead of making holes through the strap and frame, the former may be provided with notches to engage a stationary pin upon the frame. This construction provides for the adjustment of the plow to give the depth of furrow desired. The lever Q is rigidly attached to the swinging bail, either inside or 20 outside the frame. The swinging bail passing through the coupling, as described, the plow-beam is held at a proper elevation by the said lever Q, upon which it has a certain amount of vertical play. When it is desired to raise 25 the plow, the lever Q is pushed forward, the plow rising and carrying with it the coupler and the portion of the plow-beam to which it is attached. The forward end of the beam striking against the under side of the forward portion of the sulky-frame, the said frame acts as a pivot and the plow is raised therefrom as a center, whereby the plow is raised with a small movement of the bail. The team is hitched to the forward end of the plow-beam in the ordinary manner.

Having thus described my invention, I claim—

1. A U-shaped stub-axle having the arm which is journaled in the vehicle-frame parallel to and pointing in the same direction as the arm bearing the wheel, as and for the purpose shown and set forth.

2. The combination, with a bearing-plate having a bearing and a segmental slot concentric with the bearing, of a U-shaped stub-axle having its arms parallel and pointing in the same direction, and having its shorter arm rocking in the bearing and the longer arm projecting through and sliding in the segmental slot, as and for the purpose shown and set forth. 5c

3. The combination, with a sulky-frame provided with a bearing-plate having a circular opening and a curved slot therethrough, of a U-shaped axle having its arms passing through the curved slot and circular opening, 55 substantially as described.

4. The combination, with a sulky-frame provided with a bearing-plate having a circular opening and a curved slot therethrough, of a U-shaped axle having its arms passing through the circular opening and curved slot, and a lever having its fulcrum upon the arm passing through the opening in the bearing-plate and having one end secured to the arm of the axle sliding in the slot, as and for the purpose 65 shown and set forth.

5. The combination, with a sulky-frame having two bearing-plates, each provided with a circular opening and a curved slot, and two U-shaped axles mounted in said aperture and 70 slots, of a lever operatively engaging both ends of one axle, and a collar mounted on the arm of the opposite axle, passing through the slot in its bearing-plate, and having a strap attached to said collar, and means for adjusting 75 said strap, substantially as described.

In testimony whereof I affix my signature in presence of two witnesses.

GEO. H. FOWLER.
